(57) **CLAIM**

The ornamental design for a card reader device with key locking mechanism and image capturing means, as shown and described.

DESCRIPTION

FIG. 1 is a top perspective view of the invention.

FIG. 2 is a bottom perspective view of the invention.

FIG. 3 is a top plan view of the invention.

FIG. 4 is a bottom plan view of the invention.

FIG. 5 is a left side view of the invention.

FIG. 6 is a right side view of the invention.

FIG. 7 is a top front perspective view of the invention.

FIG. 8 is a bottom perspective view of the invention; and,
FIG. 9 is a front view of the invention in use.

The broken lines in FIG. 9 depict the card reader device with key locking mechanism and image capturing means in use with an electronic card and a key inserted into the locking mechanism forming no part of the claimed design.
